UNITED STATES PATENT OFFICE.

ALEXANDER C. MABEE, OF VILLA PARK, AND DONALD H. SWEET, OF EVANSTON,
ILLINOIS.

SUPPORT.

Application filed August 23, 1923. Serial No. 653,865.

To all whom it may concern:

Be it known that we, ALEXANDER C. MABEE and DONALD H. SWEET, residing at Villa Park, in the county of Du Page and State of Illinois, and at Evanston, in the county of Cook and State of Illinois, respectively, have invented a certain new and useful Improvement in Supports, of which the following is a full, clear, concise, and exact 10 description, reference being had to the accompanying drawings, forming a part of this specification.

Our invention relates to supports for telephone instruments, and more specifically to 15 an improvement in connection with the extensible type of support commonly employed for the convenience of the user in drawing the telephone instrument toward him for use and pushing it away when it is not wanted.

One object of the invention is to eliminate unnecessary movement in using telephones, especially those which are movably mounted 20 on extensible supports to be drawn towards the user when in use.

Another object is to call the operator automatically when such a telephone is drawn towards the user, independent of any manipulation of the ear piece. Another object 25 is to bring the telephone and ear piece both into operative juxtaposition with the mouth and ear respectively of the user by a single simple movement of one hand only, leaving the other hand entirely free at all times to 30 write down memoranda or for any other purpose.

Another object is to leave both hands entirely free while conversing over the telephone.

Further objects and advantages of the invention will become apparent as the description proceeds.

In the accompanying drawings:

Figure 1 is a side elevation, and 45 Fig. 2 is a partial plan view of an illustrative embodiment of the invention; and Fig. 3 is a detail of the clamp for the ear piece support.

In the embodiment of the invention selected for illustration, we have shown an ordinary desk telephone comprising a base 10, a standard 12 and a mouth piece 14. The usual hook 16 is provided, adapted to connect and disconnect the electric circuit 50 through the instrument. Ordinarily this is

accomplished by holding the hook down with the weight of the ear piece, or by removing the ear piece to let the hook fly up under the action of a suitable spring (not shown). 60

Various types of extensible linkages are employed for the convenience of the users of such telephones. We have illustrated a standard 18 supported by an extensible linkage 20, in this instance of the lazy-tongs variety. Bracket 22 grips standards 18 and 12 to fasten them together. 65

According to the present invention suitable means are provided for supporting the ear piece 24 at all times in such a position that when the user is talking into mouth piece 14 his ear will be conveniently juxtaposed to the ear piece 24. We have illustrated a standard 26 mounted on bracket 22 by means of bolt 28 having a transverse 70 slotted hole to receive the standard. A washer 30 is provided, with arcuate notches at 32 to fit standard 26, and lock nut 34 will force standard 26 against washer 30 and washer 30 against bracket 22, to hold the 75 parts in juxtaposition by friction. When lock nut 34 is loosened, bolt 28 can rotate freely about its own axis, and standard 26 can slide through the bolt and also rotate about its own axis. Receiver 24 is attached 80 to the free end of standard 26 by a clamp 36 terminating in a sleeve 38 telescoping on standard 26 and adjustably fastened by means of set screw 40. In this way complete 85 adjustment of ear piece 24 to the precise position required by the physical characteristics of the user is provided.

Rod 26 is bent at right angles at the bottom as at 62 and terminates in an eye 64 connected by link 66 to the intermediate pivot 95 68 of link 44. When the telephone is pushed back the ear piece will swing around out of the way, and when the parts are pulled out it will swing forward into operative position. It will be obvious that the means for 100 moving the ear pieces in and out may be omitted if desired.

Suitable means associated with the extensible support are provided for automatically permitting hook 16 to rise when 105 the instrument is drawn toward the user. With a linkage type of extensible support, this means may conveniently comprise a single piece of spring wire extending through the pivotal connection at 42 be- 110

tween standard 18 and link 44 of the linkage. One end of the wire extends upward to pass through one of the other pivots 46 of link 44, whereby the wire tends to rotate 5 about point 42 as a pivot when the linkage is expanded. From pivot 42 the other end of the wire extends in any suitable or convenient way to terminate in a hook 48 overlying the narrow portion 50 of hook 16. As 10 this hook moves about point 42 of the center, its outer end 50 should preferably be curved substantially in the arc of a circle around point 42. In the embodiment shown, slight additional resilience is provided in the wire 15 by extending it forward as at 52 then laterally as at 54, then coiling it around itself as at 56 and finally forming a small coil 58 to embrace part 54 and constitute a pivot between reach 52 and the intermediate reach 20 60 extending to hook 48. It will be obvious that as far as the broader aspects of the invention are concerned, the resilience required may be provided by a helical coil located either side of pivot 42, or by employing wire of proper diameter, suitable action can be obtained without any coil at all. Any element fastened to or moving with link 44 could be an effective substitute for the wire.

Without further elaboration, the foregoing will so fully explain the gist of the invention, that others may, by applying current knowledge, readily adapt the same for use under various conditions of service. It 35 will, for instance, be obvious that by omitting the arm 62, and leaving lock nut 34 a little loose, the ear piece could be swung around the horizontal axis of bolt 28 instead of around the vertical axis of standard 26. 40 This and many other modifications and alterations may be made without eliminating certain features which may properly be said to constitute the essential items of novelty involved, which items are intended 45 to be defined and secured to us by the following claims.

We claim:—

1. In combination, a telephone instrument comprising a transmitter and a receiver, an 50 extensible support for carrying the instrument substantially horizontally to and from the user, circuit control means, and means for automatically operating said control means to adjust the circuits for talking

upon pulling the instrument toward the 55 user, and to adjust the circuits for ringing upon pushing the instrument away from the user.

2. In combination, a telephone instrument comprising a transmitter and a receiver, an extensible support for carrying the instrument substantially horizontally to and from the user, circuit control means, and means for automatically operating said control means to adjust the circuits for talking 60 upon pulling the instrument toward the user, and to adjust the circuits for ringing upon pushing the instrument away from the user, said instrument including a support for holding said receiver spaced from said transmitter.

3. In combination, a telephone instrument comprising a transmitter and a receiver, an extensible support for carrying the instrument substantially horizontally to and from 75 the user, circuit control means, means for automatically operating said control means to adjust the circuits for talking upon pulling the instrument toward the user, and to adjust the circuits for ringing upon pushing 80 the instrument away from the user, said instrument including a support for holding said receiver spaced from said transmitter, said support being movable, and connections for retracting said support when the entire 85 instrument is pushed away from the user.

4. The combination with a lazy tongs support and a telephone instrument mounted on the extensible end thereof, said instrument including a receiver and a transmitter, 90 of circuit controlling means movable into two positions, i. e. a first talking position and a second ringing position, and a connection for automatically shifting said circuit controlling means from the second to the 95 first position upon extension of said support, and vice versa.

5. In combination, a telephone desk stand including a transmitter, a receiver and a switch hook, a horizontally extensible support for said desk stand, and means controlled by the movement of said extensible support for raising and lowering the switch hook independently of said receiver.

In witness whereof, we hereunto subscribe 105 our names this 13th day of August, 1923.

ALEXANDER C. MABEE.
DONALD H. SWEET.
